Des. 141,688

THERMOSTAT OR THE LIKE

Filed March 24, 1945

FIG. 1.

FIG. 2.

FIG. 3.

Inventor:
Marvin C. Lindeman,
By Clinton Wiley Schroeder,
Merriam, Kansas, U.S.A.

UNITED STATES PATENT OFFICE

141,688

DESIGN FOR A THERMOSTAT OR THE LIKE

Marvin C. Lindeman, Holland, Mich., assignor to
Holland Furnace Company, Holland, Mich., a
corporation of Delaware

Application March 24, 1945, Serial No. 118,673

Term of patent 14 years

(Cl. D52—7)

To all whom it may concern:

Be it known that I, Marvin C. Lindeman, a citizen of the United States, residing at Holland, county of Ottawa, State of Michigan, have invented a new, original and ornamental Design for a Thermostat or the like, of which the following is a specification, reference being had to the accompanying drawing, forming a part hereof.
In the drawing:

Fig. 1 is a front elevational view of a thermostat or the like embodying my new design.

Fig. 2 is a top plan view thereof.

Fig. 3 is an elevational view looking at the left hand end of Fig. 1.

I claim:

The ornamental design for a thermostat or the like substantially as shown.

MARVIN C. LINDEMAN.
